DESIGN FOR A PIANO CASE

Marion Y. Rich, Cincinnati, Ohio, assignor to The Baldwin Company, Cincinnati, Ohio

Application July 2, 1935, Serial No. 57,497

Term of patent 3½ years

To all whom it may concern:

Be it known that I, Marion Y. Rich, a citizen of the United States, residing at Gilbert Avenue and Eden Park Entrance, in Cincinnati, in the county of Hamilton and State of Ohio, have invented a new, original, and ornamental Design for a Piano Case, of which the following is a specification, reference being had to the accompanying drawing, forming part thereof.

I claim:

The ornamental design for a piano case, as shown.

MARION Y. RICH.
